UNITED STATES PATENT OFFICE.

MARIE K. TOVEY, OF ANACOSTIA, DISTRICT OF COLUMBIA.

DEVICE FOR MAKING MARCEL WAVES.

No. 901,003.

Specification of Letters Patent.

Patented Oct. 20, 1908.

Application filed February 1, 1908. Serial No. 413,899.

To all whom it may concern:

Be it known that I, MARIE K. TOVEY, a citizen of the United States, residing at Anacostia, in the District of Columbia, have invented certain new and useful Improvements in Devices for Making Marcel Waves, of which the following is a specification.

This invention relates to devices for waving the hair on the human head, and particularly to devices for producing what is known as the "Marcel wave."

The prime object of my invention is to produce an efficient device of this character for use in a household (thus avoiding hair-dressers' bills) and at such small cost as to be available to persons of moderate, or even small, means.

With this and minor objects in view, the invention consists, broadly, in a waving device comprising a metal cap to approximately fit the head, and having the required corrugations, and a similarly shaped cap of greater diameter, the latter to be heated and the hair drawn up or down between the two caps, to have the wave imparted by heat applied through the outer cap while the hair is confined between the inter-fitting corrugations of the two caps.

My invention further consists in the combination with the primary corrugated cap, protecting the scalp from heat, and the second or heating cap fitting thereover, of a heating cone adapted to impart heat derived from any suitable source to the second or heating cap, thereby insuring that the latter shall be free from contamination of smoke from a gas flame or heater, or from other source of heat.

In the accompanying drawings: Figure 1 is a side elevation of my primary cap upon the head. Fig. 2 is a similar view with the hair drawn up over the corrugations. Fig. 3 is a similar view, showing the heating cap seated over the hair and primary cap. Fig. 4 is a vertical section through the two caps. Fig. 5 is a view, partly in section, showing the heating cone upon a gas heater, and the heating cap nested upon that.

Referring to the drawings, a metal cap 1 is provided, bowl-shaped to approximately fit the head, said cap having a plurality of circumferential corrugations 2 of greater or less extent, according as a long or short wave is to be produced in the hair operated on. I have shown the cap as having four corruga-

tions, which would produce waves something more than a half inch in length from the crests or lands to the furrows, but it will be understood that the width of the corrugations will be suited to produce a "wave" of 60 the prevailing style, or one desired by the purchaser of my hair waving device. This cap 1 is, as stated, of metal, preferably aluminum or copper, polished exteriorly to present no drag on the hair when the latter is 65 pressed into the corrugations of the cap, and in some instances I propose to provide this cap with a light lining 3 of felt, or other suitable material, to protect an over sensitive scalp from heat.

A similar cap 4 is provided of such greater diameter as to nest over the cap 1 with the mass of hair thereon, and press the hair, indicated by 5, into and between the matching corrugations of the two caps.

In practice the cap 4 will be heated in any suitable way to avoid soiling it, or the hair with which it comes in contact, and by the heat so imparted to the hair when confined between the corrugations of the two caps 1 80 and 4, the hair will be given a more or less permanent waved set.

The heat-imparting cap 4 may be heated in any suitable way, but, to avoid all chance of soiling the cap or hair, I provide a heating cone 6, having corrugations similar to those heretofore described, the cone being of such less diameter than the heating cap 4 that, when the two are nested, their surfaces will be in contact. This heating cone 6 is preferably, though not necessarily, made of somewhat thicker metal than the caps 1 and 4, to the end that it will stand repeated heatings over a gas jet or otherwise without detriment, and impart its heat to the heating cap 4, and may be provided at base with a spider 6^a to rest upon a small gas heater, as shown.

The primary or protective cap 1 is provided at the apex with an opening 7 within which surplage of hair may be tucked during the operation of waving, and the heating cap 4 is provided with a handle 8, preferably non-conductive, by which it may be manipulated, and is also provided at top with a ventilating opening 9 to avoid steaming hair that may be moist or oily.

In practice the heating cone 6 is placed over a gas heater 10, or other source of heat, and the heating cap 4 nested upon it to de-

rive heat therefrom without danger of being smoked from a gas flame, or soiled by any other prime source of heat that may be used.

In use the protective cap 1 will be placed 5 upon the head as in Fig. 1, and the hair drawn up over it, as in Fig. 2, the surplusage of hair going to make up the coil being tucked into the opening 7 at the apex of the cap. The heating cap 4, previously heated, is then 10 pressed down upon the hair so drawn over the primary cap 1, thus pressing the hair in between the matching corrugations of the two caps which results in giving a wave to the hair, and applying heat thereto to make 15 the wave a more or less permanent set, according to the hair operated on, and that without danger of singeing, or of soiling the hair with smoke derived from a gas heater.

As so far described, the device is adapted 20 only to wave the hair from a line extending along the brows to the nape of the neck, and to the extent of its corrugations at top, being designed with special reference to the present style of hair dressing, where the hair is 25 massed on the crown of the head in a "pompadour" style.

To adapt the device for waving the hair from the crown downward, the hair is passed up through the somewhat elongated opening 7 30 in the cap and then smoothed down over the outer surface thereof, the heating cap 4 being then pressed down upon it, as before described, the corrugations being shaped to suit that particular style, if necessary. 35 This style of wave relates to hair parted in the middle and drawn or draped down about the head and over the forehead.

This device is of especial advantage, as, aside from the saving of hair-dressers' 40 charges, there is effected a great saving of time, from the fact that the device may be used at the home, or in lodgings, thus saving the time in going to and from the hair-dress-

er's, and from the further fact that the waving operation is effected much more quickly 45 than with the hand implements heretofore in the market, of which I have knowledge.

I claim:

1. A device for waving the hair on the human head, comprising a primary cap of 50 metal having corrugations, and an opening at top; and a heating cap of metal having corrugations to match those of the primary cap, and provided with a ventilating opening and handle. 55

2. A device for waving the hair of the human head, comprising a primary cap of metal having corrugations, and an opening at top, and provided with a lining; and a heating cap of metal having corrugations to 60 match those of the primary cap, and provided with a ventilating opening and a handle.

3. A device for waving the hair on the human head, comprising a primary cap of 65 metal having corrugations, and an opening at top; and a heating cap of metal having corrugations to match those of the primary cap, and provided with a ventilating opening and non-conducting handle. 70

4. A device for waving the hair on the human head, comprising a primary cap of metal having corrugations, and an opening at top; and a heating cap of metal having corrugations to match those of the primary cap, and provided with a ventilating opening and handle; and a heating cone of slightly less 75 diameter than the heating cap, and having similar corrugations.

In testimony whereof, I affix my signature 80 in presence of two witnesses.

MARIE K. TOVEY.
